UNITED STATES PATENT OFFICE

2,099,573

ELECTRIC SWITCH

Carl P. Pepper, Fort Wayne, Ind., assignor to
General Electric Company, a corporation of
New York

Application March 3, 1937, Serial No. 128,809

9 Claims. (CL 200—152)

The present invention relates to electric switches of the type having liquid contact circuit closers for controlling the flow of current.

The object of my invention is to provide an improved construction and arrangement in switches of this type.

In the accompanying drawing, Fig. 1 is an end elevation of a switch embodying my invention; Fig. 2 is a side elevation of the switch; Fig. 3 is an exploded view of the parts for supporting the circuit closers; Fig. 4 is a fragmentary view partly broken away showing the circuit closers in the circuit closing position; and Fig. 5 is a view similar to Fig. 4 showing the circuit closers in the circuit interrupting position.

Referring to the drawing, I have illustrated my invention using liquid contact circuit closers of the type being claimed in application Serial No. 759,527, filed December 26, 1933. Such circuit closers are typical of those suitable for use in a switch embodying my invention. The circuit closers have a pair of cup-shaped terminals 1 which are separated by a diaphragm 2 of a refractory insulating material, such as a ceramic. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the circuit closer, the space enclosed by the terminals is evacuated and filled with hydrogen at a pressure of one or more atmospheres which increases the circuit interrupting capacity of the circuit closer. The diaphragm 2 is provided with an opening 5 which is submerged in the mercury when the circuit closer is in the current conducting position shown in Fig. 4. When the circuit closer is in the current interrupting position shown in Fig. 5, the opening 5 is above the mercury and the circuit between the terminals is therefore interrupted by the insulating diaphragm 2. Due to the construction of the circuit closer, the interruption of the circuit between the terminals takes place in the mercury as the circuit closer is turned from the position shown in Fig. 4 to the position shown in Fig. 5.

The structure for supporting the liquid contact circuit closers comprises a shaft 6 which is journaled in a suitable support 7. A handle 8 for rotating the shaft is fixed to one end thereof. The shaft has a squared end 9 which fits into a square opening in the handle. When the handle is in place, the squared end is upset to form a shoulder 10 which holds the handle on the shaft,

On the shaft 6 are plates 11 and 12 of insulating material having notches 13 and 14, the sides of which fit in grooves 15 and 16 on opposite sides of the shaft. The sides of the notches 13 and 14 cooperate with the bottom of the grooves 15 and 16 to key the plates to the shaft. Contacts 17 are riveted in the plates, the contacts having round heads 18 which fit in complementary depressions 19 in the terminals of the circuit closers and tubular shanks which extend through the plates. Between the plate 11 and the heads 18 of the contacts are clamped metal parts 20 having tongues 21 which extend in depressions 22 in the adjacent circuit closer terminals and locate the angular position of the circuit closers with reference to the plates. The parts 20 also have tongues 23 which fit in one of the openings 24 or the notches 25 in the plate 11. The angular position of the circuit closers may be adjusted by turning the parts 20 so that the tongues 23 fit in a different opening or notch. The plates 11 and 12 are clamped together and held on the shaft by a bail 26 having eyes 27 fitting over the shaft. The intermediate portion of the bail fits in notches 28 in the plates 11 and 12 and thereby exerts a force clamping the plates together and holding the plates on the shaft. The grooves 15 are sufficiently wider than the plate 11 to permit the necessary movement of the plate 11 toward the plate 12 so that the circuit closers are firmly held between the plates. Leads 29 are soldered into the ends of the tubular shanks of the contacts 17 and the ends of the leads are held in position by extending the leads inward through openings 30 in the plates. A spacing washer 31 prevents axial movement of the shaft 6 in the support 7.

In the assembly of the switch, the washer 31 and the bail 26 are assembled on the shaft 6. The circuit closers are next arranged between the plates 11 and 12 with the tongues 21 fitting in the depressions 22 in the adjacent circuit closer terminals. The plates are then clamped together and placed on the shaft, the notches 13 and 14 in the plates fitting in the grooves 15 and 16 between the eyes 27 of the bail. The bail is then swung to a position in which it fits in the notches 28 thereby clamping the plates together and holding the circuit closers between the plates and the plates on the shaft. When in the clamping position, the intermediate portion of the bail is stretched. The clamping force therefore is due to the resilience of the bail. From one aspect, the bail can be considered as a tension member.

The switch is operated by turning the shaft 6

by means of the handle 8. When the switch is in the position illustrated in Fig. 4, the circuits are completed through the circuit closers. When the switch is in the position shown in Fig. 5, the 5 circuits are interrupted.

What I claim as new and desire to secure by Letters Patent of the United States, is:

1. In an electric switch, a liquid contact circuit closer having opposed terminals, a shaft, spaced 10 plates on said shaft having contacts adapted to engage said terminals, and a bail having its ends connected to said shaft and its center portion engaging said plates for clamping the plates together whereby the circuit closer is held there- 15 between.

2. In an electric switch, a liquid contact circuit closer having opposed terminals, a shaft, spaced plates having notches non-rotatably 20 engaging complementary portions on said shaft, contacts on said plates adapted to engage said terminals, and a bail having its ends connected to said shaft and its center portion engaging said plates for clamping the plates together whereby the circuit closer is held therebetween and for 25 holding the plates on said shaft.

3. In an electric switch, a support, a liquid contact circuit closer having opposed terminals, spaced members on said support carrying contacts adapted to engage said terminals, one of 30 said contacts and said terminals having interfitting projections and depressions whereby the circuit closer is supported between said contact carrying members, and a tension member having its ends connected to said support and its center 35 section engaging one of said contact carrying members for clamping said members together whereby the circuit closer is held therebetween.

4. In an electric switch, a liquid contact circuit closer having opposed terminals, contacts 40 adapted to engage said terminals, members carrying said contacts, a support, and means including a tension member extending from said support over an edge of at least one of said contact carrying members for clamping the contact carrying members together whereby the circuit closer is held therebetween.

5. In an electric switch, a support, a liquid contact circuit closer having opposed terminals, contacts adapted to engage said terminals, one

of said terminals and said contacts having interfitting portions whereby angular displacement of the circuit closer relative to the contacts is prevented, members carrying said contacts, at least one of which is movable toward the terminals of 5 the circuit closer, and a tension member having its ends secured to said support and having an intermediate portion engaging an edge of said movable contact carrying member for clamping said members together.

6. In an electric switch, a liquid contact circuit closer having opposed terminals, contacts adapted to engage said terminals, members carrying said contacts, a shaft non-rotatably carrying 10 said members, one of said members being movable lengthwise of said shaft, and means clamping 15 said members together whereby the circuit closer is held therebetween.

7. In an electric switch, a liquid contact circuit closer having opposed terminals, depressions in 20 said terminals, contacts adapted to engage said terminals and having projections thereon fitting in said terminals, members carrying said contacts, and means clamping said members together whereby the circuit closer is held there- 25 between.

8. In an electric switch, a liquid contact circuit closer having opposed terminals, a depression in one of said terminals, contacts adapted to engage said terminals, one of said contacts having 30 a tongue fitting in said depression whereby the circuit closer is held in fixed angular relation with respect to the contact members carrying said contacts, and means clamping said members together whereby the circuit closer is held 35 therebetween.

9. In an electric switch, a liquid contact circuit closer having opposed terminals, a depression in one of said terminals, contacts adapted to engage said terminals, members carrying said 40 contacts, an opening in one of said members, one of said contacts having tongues respectively fitting in said depression and said opening whereby the circuit closer is held in fixed angular relation with respect to said contact, and means 45 clamping said members together whereby the circuit closer is held between said contacts.
